UNITED STATES PATENT OFFICE.

WILLIAM S. ROBINSON, OF FANCY FARM, KENTUCKY, ASSIGNOR, BY DIRECT AND MESNE ASSIGNMENTS, OF THIRTEEN-SIXTEENTHS TO FRANCIS X. PIERCEALL, WILLIAM O. BALLARD, CHARLES A. HAESELEY, JOSEPH M. WILLETT, THOMAS J. ROBB, AND WILLIAM B. WILLETT, OF SAME PLACE.

TRANSOM-LIFTER.

SPECIFICATION forming part of Letters Patent No. 527,347, dated October 9, 1894.

Application filed June 11, 1894. Serial No. 514,243. (No model.)

To all whom it may concern:

Be it known that I, WILLIAM S. ROBINSON, a citizen of the United States, residing at Fancy Farm, in the county of Graves and State 5 of Kentucky, have invented new and useful Improvements in Mechanism for Opening Windows, Transoms, &c., of which the follow is a specification.

My invention relates to mechanism for operating window sashes, transoms or similar structures, of that class which are hung or journaled to swing or revolve in the window frame, and it has for its objects to provide a mechanism actuated to open and close the window sash by a single operating device; to provide a mechanism for which the bolt fastening the sash in its closed position is released and the sash swung to the desired open position by a single, continuous action of the operating device; to provide a mechanism wherein the sash is released from its locked, closed position, swung to the desired open position and automatically held in such open position; to provide a mechanism wherein 15 the sash is swung to and held in open position and released from the adjusted open position to swing automatically to its closed position, by a single operating device; and finally said invention has for its object to improve generally the construction and operation of window sash operating mechanism.

To these ends said invention consists in the novel construction of parts; in the novel combination of parts and in the novel arrangement and operation of parts hereinafter described and claimed, reference being had to the accompanying drawings, wherein—

Figure 1 is a side elevation, the sash being in a slightly open position. Fig. 2 is a front view, 40 the operating mechanism being arranged to operate two adjoining windows. Fig. 3 is a detail side view, the mechanism being in its normal position or that position it takes when the sash is closed. Fig. 4 is a perspective view, the parts being detached and in their relative position when the window has been released from its adjusted open position and is about to automatically swing to its closed position. Fig. 5 is a detail perspec-

tive view of the crank lever hereinafter described.

In said drawings the reference-numeral 1, designates a window-frame and 2 a sash journaled to swing or revolve therein on studs 3. A bracket or other suitable support 4, constructed preferably in two sections 4^a and 4^b connected together by a pin 5, is designed to be secured to the face of the window frame 1, at the side of the window sash and in or about the same horizontal line with the pivotal support 3 of said sash, and journaled to turn in said bracket is an axle 6, having elongated spindles 6^a. Said axle carries a rigidly fixed arm 7, adapted to be moved in a vertical plane to rock or rotate the axle in 65 its bearings.

The numeral 8, represents a crank-lever adapted to be fitted upon the axle 6, at varying positions of adjustment, dependent upon the distance from the inner edge of the window-frame at which the bracket 4, is located. Secured to the side of the window sash adjacent to the bracket and at a point above the pivoting studs 3, is a plate 9. Connected pivotally at its opposite ends to said crank-lever 8 and said plate 9 is a link 10, whereby an operative connection is established between the window sash and the sash-swinging arm 7. It is found that in different windows the sashes are arranged at various distances from the face of the window frame, and to accommodate the mechanism to such variously arranged sashes I provide a means of adjusting the operative length of the link 10, which consists of two series of perforations 11 formed in said link and the connecting arm of the crank-lever 8, said perforations being adapted to be brought into register and the link and lever connected at the desired adjustment by means of a pin or other device. 90

The numeral 12, indicates a sliding bolt secured to the window sash and adapted to engage a bolt socket in the sill to lock the sash in its closed position. Running from the upper end of this bolt and over a pulley or movable anti-friction device 13 at the top of the sash is a flexible connecting medium which at its other end is secured to a ring or

analogous element 14, said ring being located slightly above the outer end of the arm 7, when said arm is in its elevated or normal position. An operating device 15, is secured 5 at one end to said ring and passes through an eye formed in the outer end of the arm 7, its other end extending to any suitable point within reach of the operator. The provision and arrangement of the ring or other connecting element 14, is made so that a pull upon the operating device 15 will release the bolt prior to coming into operative engagement with the arm 7.

The operation of the mechanism as thus far 15 described will be obvious to those skilled in the art, but may be briefly stated as follows: The window sash being in its closed and locked position a pull upon the device 15, will release the bolt, unlocking the sash and leaving it free to be opened. A continuance of the pull brings the ring 14 into contact with the outer end of the arm 7 which is carried downward with the ring, whereby the axle 6 is rocked or rotated and through the instrumentality of the crank-lever 8 and link 10, the 20 sash is swung from its closed position to an open position, as will be understood and as shown in Fig. 1.

It is desirable that the sash may be opened 30 to greater or less extent for ventilation, according to the condition of the weather and that when opened it shall be held in its position of adjustment. For this purpose I form ratchet teeth 16, of desired number and 35 distance apart in the hub or butt-end of the arm 7, and upon the bracket 4, I provide a pivoted pawl 17 which automatically drops into engagement with one or another of the teeth 16, according to the degree to which the 40 window sash is to be opened, and thus securely holds the sash in that position.

In order to release the pawl 17 from the teeth, to permit the window sash to assume its closed position, I employ the following instrumentalities: Upon the bracket 4 is pivoted a swinging trip-dog 18, the active end of 45 which lies behind the pawl 17, and at a predetermined distance in rear thereof upon the hub of the arm 7, is arranged a fixed finger 50 19, whereby upon the operator drawing downward upon the device 15, the said finger 19, strikes against the trip-dog 18 which in its forward movement lifts the pawl 17 from engagement with the teeth 16, and holds it out 55 of engagement until the arm is elevated when it is thrown into operative position as herein-after described. The arm 7 is thus released and the sash will automatically, by its own gravity, swing to its closed position. In 60 cases where the pivotal engagement of the sash will not permit it to swing closed by gravity any suitable device can be employed, such as a spring, to draw the arm to its normal, elevated position and close the sash 65 when the pawl is released from the teeth.

In order to prevent the arm 7, descending too far and thus allowing the trip-dog to

swing out past the pawl 17, a spring or elastic stop-plate 20 is secured to the bracket 1, and at its outer end engages a seat 21, in the 70 arm 7, when the said lever has been lowered the proper distance to release the pawl 17. This stop-plate also serves as a guard to prevent the lever being drawn down far enough to release the pawl when it is desired to open 75 the window, as its outer end will meet said arm at the proper time in its descent and offer sufficient resistance to notify the operator that the window-sash has been brought to its wide open position. 80

When the arm has been released and is carried to its elevated position by the window in closing (or by a device such as a spring in windows differently hung) the inclined nose of the pawl 17 will strike against the 85 arm 7 and swing the trip-dog back, when the parts will be in correct relative position for operation.

I have described my invention as applied 90 for use in operating a single window, transom or similar structure, but it is obvious that it is adapted to be used to operate two adjoining structures, as shown in Fig. 2, the only change necessary being the provision of an additional locking bolt, a flexible connection thereof with the ring 14, and a second bell-crank-lever and link. 95

Having thus described my invention, what I claim is—

1. In mechanism for operating swinging 100 windows, transoms and like structures, the combination with a sash-locking device, of an axle, means connecting said axle with a window-sash, a swinging arm carried by said axle, and a device operatively connected to 105 said sash-locking device and to said swinging arm, for unlocking the sash and swinging the same to an open position, substantially as described.

2. In mechanism for operating swinging 110 windows, transoms and like structures, the combination with a sash and a locking device therefor, of an axle, a crank lever secured to said axle, a link pivotally connected to 115 said sash and said crank lever, a swinging arm carried by said axle, and a device operatively connected to said sash-locking device and to said swinging arm, for unlocking the sash and swinging the same to an open position, substantially as described. 120

3. In mechanism for operating swinging 125 windows, transoms and the like, the combination with an axle, means connecting said axle with a sash, a sash-swinging arm carried by said axle, means for holding said arm in various positions, and a finger carried by and automatically releasing said arm, substantially as described.

4. In mechanism for operating swinging 130 windows, transoms and the like, the combination with a movable sash-swinging arm, means for connecting said arm with a sash, a device for holding said arm in varying positions, and means carried by said arm for re-

leasing the holding device, substantially as described.

5. In mechanism for operating swinging windows, transoms and the like, the combination with a movable sash-swinging arm, means for connecting said arm with a sash, a pawl and ratchet mechanism for holding said arm in varying positions, a pivoted trip-dog, and a finger carried by said arm to actuate said trip-dog to disengage the pawl and ratchet mechanism, substantially as described.

6. In mechanism for operating swinging windows, transoms and the like, the combination with a movable sash-swinging arm, means for connecting said arm with a sash, a pawl and ratchet mechanism for holding said arm in varying positions, a pivoted trip-dog, a finger carried by said arm to actuate 20 said trip-dog to disengage the pawl and ratchet mechanism, and a stop to limit the movement of said arm, substantially as described.

7. In mechanism for operating swinging windows, transoms and the like, the combination with a bracket, an axle carried thereby, an arm fixed on said axle, a crank lever fitted to said axle, a link pivotally connecting said

lever to a sash, pawl and ratchet mechanism for holding said arm in various positions of adjustment, a trip-dog pivoted to the bracket and lying behind the pawl, and a finger carried by the arm and adapted to strike the trip-dog and release the pawl and ratchet mechanism in the movement of said arm, substantially as described.

8. In mechanism for operating swinging windows, transoms and the like, the combination of a sash locking device, a movable arm connected with the sash, means for holding said arm in various positions of adjustment, means for releasing said arm, and a device engaging said locking device and arm which in its continued movement releases the sash locking device, and actuates the movable arm to open the sash and to release itself to allow the sash to close, substantially as described.

In testimony whereof I have hereunto set my hand and affixed my seal in presence of 50 two subscribing witnesses.
